US00D514884S

(12) **United States Design Patent** (10) Patent No.: **US D514,884 S**
Smith et al. (45) Date of Patent: **** Feb. 14, 2006**

(54) **ERGONOMIC DISPOSABLE CUP**

(75) Inventors: **Stephen Alan Smith**, Naperville, IL (US); **Kevin Ray Smith**, Round Lake Beach, IL (US); **Warren Giles Wiedmeyer**, Trevor, WI (US); **Kimberly Vaile Healy**, Chicago, IL (US); **Randy Golden**, Ada, OK (US); **Rudy DesChamps**, Mahomet, IL (US); **Irshad Khan**, Round Lake Beach, IL (US); **Bryce C. Rutter**, St. Louis, MO (US); **Brian C. Bone**, St. Louis, MO (US); **John H. Loudenslager**, Phoenix, AZ (US); **Jan Rolf Stillerman**, Phoenix, AZ (US)

(73) Assignee: **Solo Cup Company**, Highland Park, IL (US)

(**) Term: **14 Years**

(21) Appl. No.: **29/217,996**

(22) Filed: **Nov. 23, 2004**

Related U.S. Application Data

(60) Division of application No. 29/194,964, filed on Dec. 3, 2003, now Pat. No. Des. 505,830, which is a continuation-in-part of application No. 10/676,807, filed on Oct. 1, 2003.

(57) **CLAIM**

We claim the ornamental Design for an ergonomic disposable cup, as shown and described.

DESCRIPTION

FIG. 1 is a perspective view of a first embodiment of the cup of the present invention;

FIG. 2 is a front elevation view of the cup of FIG. 1, with an opposite view being identical thereto;

FIG. 3 is a side elevation view of the cup of FIG. 1, with an opposite view being identical thereto;

FIG. 4 is a top plan view of the cup of FIG. 1;

FIG. 5 is a bottom plan view of the cup of FIG. 1;

FIG. 6 is a perspective view of a second embodiment of the cup of the present invention;

FIG. 7 is a front elevation view of the cup of FIG. 6, with an opposite view being identical thereto;

FIG. 8 is a side elevation view of the cup of FIG. 6, with an opposite view being identical thereto;

FIG. 9 is a top plan view of the cup of FIG. 6; and,

FIG. 10 is a bottom plan view of the cup of FIG. 6.

Broken lines in the Figures form no part of the claimed design.
